Primary Examiner—Bernard Ansher
Attorney, Agent, or Firm—Richard H. Brink[57] **CLAIM**

The ornamental design for a tibial template for knee joint reconstruction, as shown and described.

DESCRIPTION

FIG. 1 is a front elevational view of a tibial template for knee joint reconstruction;

FIG. 2 is a bottom plan view thereof;

FIG. 3 is a top plan view thereof; and

FIG. 4 is an auxiliary view thereof taken along line 4 — 4 of FIG. 1.
